UNITED STATES PATENT OFFICE.

GEORGE F. ALBRO, OF LOS ANGELES, CALIFORNIA.

COMBINED OFFICE AND DROPHEAD TYPEWRITER-DESK.

1,398,618.

Specification of Letters Patent. Patented Nov. 29, 1921.

Application filed March 18, 1920. Serial No. 366,973.

To all whom it may concern:

Be it known that I, GEORGE F. ALBRO, a citizen of the United States, residing at Los Angeles, in the county of Los Angeles and State of California, have invented a new and useful Combined Office and Drophead Type-writer-Desk, of which the following is a specification.

An object of the invention is to provide a drop head typewriter desk which may be used with ease and comfort as an ordinary writing desk. That is to say, drop head typewriter desks as constructed prior to this invention, have been so arranged that when the typewriter is inclosed, the shelf which carries the same prevents the knees of the writer from extending under the desk top far enough for comfort; and an object of this invention is to provide a drop head typewriter desk in which the typewriter shelf will not be in the way of one sitting at the desk to write when the desk top is fully closed to constitute a writing desk.

The invention is pioneer in that I connect and swing the desk top and the typewriter shelf to and within the housing or desk frame by means of two levers and a connecting rod in such a way that such shelf is bodily retracted from the front of the desk as the desk top is closed, and is held retracted into approximately vertical position entirely out of the way of the knees of a person seated to write on the desk top.

An object is to provide a desk of this character of simple and cheap construction easily applied and operated.

A novel feature of the invention is that the desk top and typewriter support are oscillatably mounted in the desk frame by means adapted to swing or oscillate the desk top and typewriter shelf and to establish them in rectangular relation to each other at the end of the opening movement and at the end of the closing movement of the desk top.

An object is to raise the typewriter shelf to a higher level than heretofore when the desk is open so as to more freely accommodate lateral movement of the typewriter carriage and the hand which operates it.

Other objects, advantages and features of invention may appear from the accompanying drawing, the subjoined detail description and the appended claims.

The accompanying drawing illustrates the invention.

Figure 1 is a perspective view of a closed

typewriter desk constructed in accordance with this invention.

Fig. 2 is an elevation on the plane practically indicated by line x^2-x^4 , Fig. 1. The type-writer is indicated in dotted lines in position on the type-writer support.

Fig. 3 is a fragmental perspective view of the desk shown in Fig. 1 with the top thrown open and the type-writer shelf or support ready to receive a type-writer.

Fig. 4 is a fragmental sectional elevation of the type-writer desk shown in Figs. 1 and 2 and open as in Fig. 3, and viewed from substantially the same plane as Fig. 2.

Fig. 5 is a fragmental plan in section on different horizontal planes at several pivotal axes; parts being exaggerated in thickness to clearly show what parts are pivotally and what parts are fixedly connected together.

Fig. 6 is a fragmental sectional detail of the beam which is only partly in section in Fig. 5. Fragments of the frame and desk top or closure and pivotal connection are also shown in section.

The desk top or closure 1 and the shelf 2 are of the usual construction and are mounted and movable within the housing or frame 3 by lever and link means as the beam 4, the lever 5 and link 6.

The beam 4 is a lever pivoted intermediate its ends by pivot 7 to a support formed by a part of the stationary desk frame or housing wall 3.

The drop head or separable top 1 of the desk is connected with the desk frame or housing and the type-writer shelf or support 2 by a system of lever and link connections comprising pairs of the metal straps or bars above referred to, in combination with each other and with the type-writer desk or housing and the drop head and shelf; there being one set of each of said lever and link connections at each lateral edge of the type-writer shelf and the drop head or top; said drop head and shelf, together with the bars, forming a unit, and being mutually and eccentrically adjustable, relative to the desk housing or frame.

The beam 4 is pivoted to the desk top 1 by a pivot 8 through a fixture 9 that is attached to said desk top; and said beam is pivoted by a pivot 10 to the shelf 2 through the medium of a reinforcing bar or strap 11 that is fixed to the shelf by screws 12. The lever 5 is pivoted to the desk top by a pivot 13 through the medium of a block 14 that is

fixed to said desk top; and said lever 5 is pivoted by a pivot 15 to the frame or housing 3, and by a pivot 16 to the link 6 which in turn is pivoted by pivot 17 to the shelf 2 through the medium of said reinforcing strap 11. 18 is a latch by which the typewriter shelf may be latched to the frame 3 when the top 1 is dropped. Said shelf is also provided with means, as the bolt holes 10 19, for attaching the typewriter to the shelf.

The relative lengths of the beams, levers and links may be determined, according to the principle of this invention, to afford a greater or less depth of recess under the 15 closed top between the front or under side of the shelf and a vertical line drawn down from the front edge of the desk top when closed.

In the instance shown it may be assumed 20 that such recess is eight inches deep.

There are two fixed pivotal axes, one at 7 and the other at 15 over which the top is oscillatable from horizontal top position to up and down back position, and vice versa 25 while the shelf is connected to oscillate from horizontal position intermediate said axes to up and down position in front of said axes. To effect this, the beams, levers, links and pivots are so disposed that when the top 30 and shelf are in closed position, the top and the upper lever 5 is horizontal, and its pivotal points 13, 15 and 16 are horizontally alined, the shelf stands upright in front of the beam and lever pivots, the beam 4 stands 35 upwardly and rearwardly aslant and the link 6 is in front thereof, is parallel to the beam, and extends between the fixed axes 7 and 15.

The beam 4 is pivoted to the frame 3 about 40 midway between the free ends of the lever, the rear end of which is pivoted to the rear edge of the desk top, and the front end to the middle of the shelf, while the lever 5 is pivoted near the end which is nearest the 45 rear when closed.

The long end of the lever 5 is pivoted near the front edge of the cover and the short end is connected to the shelf near the front edge thereof by the link.

50 By this construction and arrangement the weight of the shelf and of the typewriter indicated in broken lines at 20 is carried by the pivots 7 and 15 about which the desk top and typewriter oscillates during opening 55 or closing of the desk.

The desk top is shown with the usual lock 21 and pull 22.

In practical manufacture the beams 4, levers 5, links 6, and shelf bars 11 will all 60 be cut from strap iron or steel and punched or bored to form the purchases for the pivots and the holes for the screws 12.

Then they may be assembled and the parts for each side set or assembly including the 65 fixture 9, will be assembled and pivoted to-

gether as shown, and then the bars 11 of the companion sets or assemblies will be fastened to the shelf by screws 12. Then the top 1 will be pivoted at 8 and 13 to the oscillating mechanism, and the connected parts 70 will all be brought into the frame or housing in the position shown in Fig. 3 and in solid lines in Fig. 4, and then pivots 7 and 15 are set; whereupon the desk is ready for the typewriter which will be fastened to the 75 shelf in the usual manner.

It is thus seen that I have swung the desk top and typewriter support or shelf on two pivotal axes in a frame by oscillating mechanism comprising the beams, levers and links 80 so arranged, as described, that the desk top and support will be in relative rectangular positions at open and closed positions of the desk top. The forward edge of the shelf or support, when in open position, is spaced 85 from the front of the desk and lies approximately in a common plane with the under surface of the desk top when in closed or vertical position.

In practice the assemblies composed of the 90 bar, the beam, the lever, and the link, and the purchase, pivoted together, but free from the desk frame, top and shelf are provided independently of the desk structure and the operation of setting up; so that the assemblies 95 may be kept in stock, and may be shipped and stored ready for application to the desk frame, top and shelf and may be readily applied thereto by unskilled laborers with screw drivers as the only tools.

By the construction shown the parts may 100 be so proportioned as to bring the typewriter shelf to any desired level when the desk is opened.

I claim.

1. The combination with a housing, of a 105 desk top and a shelf mounted and movable within the housing, and means connecting the shelf with the desk top and adapted to transmit motion from the desk top to the 110 shelf to move the shelf into approximately horizontal position when the desk top is moved into approximately vertical position within the housing and at such a distance rearwardly from the front of the housing as 115 to accommodate the knees of one sitting at the desk when the desk is closed; and to move the shelf into approximately vertical position within the housing when the desk top is moved out of the housing and into 120 horizontal position.

2. The combination with a frame, a desk 125 top and a typewriter shelf; of a beam pivoted at about its middle to the frame and pivoted at its ends to the back of the desk top and to the typewriter shelf at about the middle of said shelf; a lever pivoted near one end to the frame and pivoted at its long end to the front of the desk top; and a link pivoted at one end to the short end of the 130

lever and pivoted at the other end to the front edge of the shelf.

3. The assembly for connecting a desk top and a typewriter shelf to a frame, which 5 consists of a strap iron bar provided with pivot holes at its ends and adapted to be fixed to the edge of a typewriter shelf, a strap iron beam provided with pivot holes at the middle and both ends, a strap iron 10 lever provided with pivot holes at its ends and between its middle and one end; a link provided with pivot holes at its ends; pivots pivoting the link at one end to the short arm of the lever and at the other end to one 15 end of the bar, and a pivot pivoting one end of the beam to the other end of the bar, substantially as and for the purpose set forth.
4. A combined office and typewriter desk 20 in which the desk top and typewriter shelf are swung to and within the housing or desk frame by means of two levers and a link in such a way that the front edge of such shelf is bodily retracted from the front 25 edge of the desk as the desk top is closed and is held practically vertical and the front edge of such shelf in such retracted position is spaced from the front edge of the

desk so as to be out of the way of the knees of the person seated to write upon the desk 30 top when the desk is closed.

5. In a desk, the combination with a housing, of a shelf and a separable top, and means pivotally connected to said shelf, top and housing, and being adapted and arranged to bring said shelf and top into open and closed positions; said means comprising a lever pivoted between its middle and one end to the housing and arranged parallel to said top when the desk is in closed position, 35 the long end of said lever being pivotally connected to the forward edge of said top; a link pivotally connected to the short end of said lever and to said shelf, and a beam pivotally connected intermediate its ends to the housing and pivotally connected at one end to the rearward edge of said top and pivotally connected at the other end to said shelf.

In testimony whereof, I have hereunto 50 set my hand at Los Angeles, California, this 11th day of March, 1920.

GEORGE F. ALBRO.
